UNITED STATES PATENT OFFICE.

THOMAS H. KING, OF CHARLOTTE, NORTH CAROLINA.

CARPENTER'S SCRIBER.

Application filed January 5, 1923. Serial No. 616,833.

To all whom it may concern:

Be it known that I, THOMAS H. KING, a citizen of the United States, residing at Charlotte, in the county of Mecklenburg and State of North Carolina, have invented new and useful Improvements in Carpenters' Scribes, of which the following is a specification.

The object of this invention is to produce a scribe for carpenters' use which will materially facilitate the accurate cutting of boards or timbers that are designed to have their ends in contacting engagement with uprights or other timbers.

The drawings which accompany and form part of this application, illustrate a satisfactory embodiment of the improvement reduced to practice, and wherein:—

Figure 1 is a view illustrating the manner in which the tool is employed for scribing siding boards so that the same will accurately engage the corner post of a building.

Figure 2 is a view showing the manner in which the device is employed for scribing a base board with respect to the vertical stile of a door casing.

Figure 3 is a view showing the manner in which the tool is employed for scribing the upper board of a door casing so that the same will accurately engage the mitered upper edge of the vertical board or stile of the casing.

Figure 4 is a perspective view of the tool.

Figure 5 is an approximately central vertical longitudinal sectional view therethrough.

Figure 6 is a sectional view on the line 6—6 of Figure 5.

Remaining views illustrate details.

In frame building constructions the outer or siding boards 1 are designed to be cut transversely so that the ends thereof will snugly fit against the corner board 2. As the siding boards are necessarily of a length greater than the distance between the corner boards 2, precision in cutting the boards in order that a tight joint may be made between the sidings and the corner posts, is an absolute necessity. The siding boards are arranged inlapping relation and therefore an ordinary rule or square cannot be successfully used in scribing the boards. In carrying out my invention, I make use of a tool that includes parallel arms, and which arms are connected at one of their ends by what I will

term a head. Each arm includes an inner member 3 which has its sides beveled inwardly from its outer face to a suitable distance away from its inner face, and whereby the outer face of each of the arms 3 is formed with a dove-tailed tongue 4.

The outer or slidale member for each arm 3 is indicated by the numeral 5, the same having its inner face provided with a dove-tailed groove 6 to receive the tongue 4. Suitable binding means 7 is provided upon the outer members 5 to contact with the tongues 4 of the inner members 3,

whereby the outer members may be suspended adjusted on the inner members. Each inner member or arm 3 has one of its ends both thickened and widened to provide shoulders 8 against which the slidale members 5 abut when the same are moved

thereagainst. The ends of the arms just referred to, indicated for distinction by the numeral 9, each have a squared opening 10 therethrough, and is further provided with a threaded opening through

so which a binding screw 11 passes, the said screw entering the opening 10 to engage a block 12 that is received through the openings and that passes through squared openings 13 in the block sections 14 that

constitute the head. Any desired number of block sections are employed, whereby the arms of the tool are sustained at determined spaced relations so that the siding or other boards of different thicknesses may

be received between the arms.

The thicker block 14 has its opposed faces provided with projecting lugs 15 that are designed to be received in openings 16 on the inner faces of the narrower blocks, when the latter are employed, the outer faces of the narrower blocks being provided with lugs 17, and these lugs as well as the projecting lugs on the first mentioned block are designed to be received in openings 18 on the inner faces of the arm sections 3. In this manner, a tight joint is at all times sustained between the head sections and the arms.

On one of the outer sections 5 of one of the arms there is a projecting lug 19 having a dove-tailed opening therethrough to receive a cross sectionally dove-tailed shaped rule 20, suitable binding means 21 passing through the lug and contacting the rule. The rule provides the device with a gauge whereby the lap of the siding

105

115

120

boards can be accurately arranged. To accomplish this, the lug is positioned beneath a siding that is already secured, and the rule is adjusted so that the same will 5 contact with the lower edge of the siding board about to be secured.

To allow the siding boards to be properly scribed, the head sections of the improvement are adjusted so that the siding boards 10 of determined thicknesses will be properly received between the arms thereof, and the tool is thus arranged on the board and is brought so that one of its edges will contact with the inner edge of the corner board 15 2, when a scribe line is marked on the board to be cut. In this manner, an accurate cut can be made so that a tight joint will be established between the siding and the corner boards.

20 As disclosed in Figure 2 of the drawings, the tool can be successfully used for producing an accurate joint between a base board and the vertical stile of a door frame. Also, as disclosed in Figure 3, the 25 upper board of the door frame can be properly scribed to fit the miter cut at the upper end of the vertical stile. This allows a great saving of the carpenters' time, inasmuch as mitered joints produced in the usual manner require planing by what is termed a 30 block plane before an accurate fit is obtained between the joints. It is thought that the foregoing description, when taken in connection with the drawings will fully set 35 forth the construction, operation and advantages of the improvement, it being, of course, understood that the tool is susceptible to other uses than those herein described, and further that I am not to be restricted 40 to the precise structural details herein alluded to, but may make such changes therefrom as fall within the scope of what I claim.

Having described the invention, I claim:—

1. A carpenter's tool, for the purpose set 45 forth, comprising a head made up of a plurality of superimposed blocks, interengaging means between the contacting faces of the blocks, an element passing centrally through the blocks, two parallel arms extending in the same direction away from the ends of the blocks and receiving the element therethrough at opposite ends of the block, respectively, binding means between 50 each arm and the element, interengaging means between each arm and the adjacent block, each of said arms comprising an inner member secured to said element and having a dove-tailed tongue and an outer member having a dove-tailed groove to slidably receive the tongue, and binding means 55 between the outer and inner members of the arms.

2. A carpenter's tool, for the purpose set 60 forth, comprising a head made up of a plurality of superimposed blocks, interengaging means between the contacting faces of the blocks, an element passing centrally through the blocks, parallel arms extending in the same direction from the head, each 65 receiving the element therethrough, binding means between each arm and the element, interengaging means between each arm and the adjacent block, each of said arms comprising an inner member secured to said 70 element and having a dove-tailed tongue and an outer member having a dove-tailed groove to receive the tongue, and binding means 75 between the outer and inner members of the arms, a lug projecting from the outer face of one of the outer members, a rule 80 slideable through the lug, and binding means between the lug and rule.

In testimony whereof I affix my signature.

THOMAS H. KING.
